UNITED STATES PATENT OFFICE.

JAMES M. SWEENEY, OF ASPINWALL, PENNSYLVANIA.

MACHINE FOR MAKING CARBON-BLACK.

No. 836,948.

Specification of Letters Patent.

Patented Nov. 27, 1906.

Application filed March 18, 1905. Serial No. 250,770.

To all whom it may concern:

Be it known that I, JAMES M. SWEENEY, a citizen of the United States, residing at Aspinwall, in the county of Allegheny and State of Pennsylvania, have invented or discovered certain new and useful Improvements in Machines for Making Carbon-Black, of which improvement the following is a specification.

The invention described herein relates to certain improvements in the apparatus of the manufacture of carbon-black. It has heretofore been customary in the manufacture of this material to arrange the gas-burners in such relation to the surface of the plate on which the black is deposited that the flames will impinge at right angles to such surface, and in order to prevent the products of combustion from extinguishing the flame it has been necessary to arrange the burners at some distance from the receiving-surface, thereby giving an opportunity for the access of such quantities of oxygen and under such conditions as to permit of a hot flame, with the consequent result of burning a portion of the carbon before impact against the surface and also of a portion of the black already deposited.

It is the object of the present invention to so arrange the burner and deposit-receiving surface in such relation to each other that the flame will impinge against the surface at an angle less than a right angle and the flame will have a longer contact with such surface. By reason of this angular impact of the flame the point of impact will be at one side of the burner, and hence the products of combustion produced will not be thrown back directly against and around the flame, thus avoiding extinguishing the flame and permitting a closer arrangement of the burner to the deposit-receiving surface.

The invention is hereinafter more fully described and claimed.

In the accompanying drawings, forming a part of this specification, Figure 1 is a vertical section of my improved form of construction of apparatus. Fig. 2 is a horizontal section view, the plane of section being indicated by the line II II, Fig. 1. Fig. 3 is a similar view to Fig. 1, showing a modification of the apparatus. Fig. 4 is a horizontal section view on a plane indicated by the line IV IV, Fig. 3; and Fig. 5 is a detailed view, on an enlarged scale, of a form of burner.

In the form of apparatus shown in Figs. 1 and 2 the deposit-receiving surface 1 is sup-

ported at its periphery upon suitable posts or standards 2, said posts or standards being connected by cross-bars 3, to which is secured the upper bearing 4 of the hollow shaft 5. 60 This shaft extends down through a stuffing-box 6 onto a suitable bearing formed in the bearing-block 7, through which is formed a passage communicating with the hollow shaft 5. This passage is connected to a suitable 65 source of gas or oil supply, and on the shaft is secured a pulley 8, whereby the shaft may be rotated as required. Radial arms 9 are secured to the shaft in suitable relation to the plate 1, and to the outer ends of these arms 9 70 is secured an annular ring 10, provided with a series of burners 11. These burners are so constructed or arranged as to direct the flame at an angle less than a right angle and, preferably, quite acute against the plate 2. It is 75 preferred that the shaft and burners should be rotated in such direction as to exert a pull on the flame away from the burner, thereby causing a considerable extension of the flame. In order to collect the carbon-black 80 deposited on the plate, from which it is removed by scrapers 12, supported on an arm 13, carried by the shaft, a basin 14 is secured to the standards below the plate 1, the walls of such basin inclining toward an outlet-spout 15. In order to insure the removal of the carbon-black from the basin, brushes or scrapers 16 are secured to the shaft so as to sweep around the inner surface of the basin 90 and push the material into the spout. The lower end of the spout is connected to suitable means for conveying the lampblack away—such, for example, as a passage 17, in which is arranged a screw 18, adapted to push the material along the passage to the 95 discharge-opening 19.

In lieu of revolving the burners, as in the construction shown in Figs. 1 and 2, the plate 1 may be secured to a vertical shaft 5^a, having its lower end mounted in a suitable step 100 20, the shaft being supported in a vertical position by means of braces 21, preferably provided with antifriction-rollers 22, bearing against the shaft. The burners 11, which are arranged in the same relation to the plate 105 1 as in the construction shown in Figs. 1 and 2, are secured to an annular pipe 23, connected by a pipe 24 to a suitable source of gas or oil supply. The arm 13^a, carrying the scrapers 12, is secured to one of the posts or standards 2, and a hopper 14^a, having its side walls so shaped as to direct the carbon-

black removed from the plate into the channel or passage 17, is arranged below the scrapers. As shown in Fig. 4, the burners may have their tips so constructed as to give 5 a fan-like flame or to give a narrower flame, as required by conditions of work. As stated in regard to the construction shown in Figs. 1 and 2, the point of impact of the flame is moved away from the burners, so that the 10 flame will be extended and drag along the plate, or the plate will be moved along the flame, thus removing the smoke-deflecting point away from the flame and preventing any smothering or extinguishing thereof and 15 also preventing the combustion of the deposited carbon by the flame. The point at which the smoke and unconsumed gases impinge upon the plate is carried away from the burners, and as such impingement is at 20 an angle the smoke and unconsumed gases will be deflected away from the burner, and the latter can be arranged in very close proximity to the carbon-receiving surfaces, thus

25 preventing the access of such quantities or volumes of air as will produce a hot carbon-consuming flame.

I claim herein as my invention—

In an apparatus for the manufacture of carbon-black, the combination of a horizontally-arranged plate, gas-supply pipes, means 30 for moving one of said parts relative to the other, said supply-pipes having outlets arranged to direct the flame against the plate at an angle less than a right angle, and in a direction that a pull is exerted on the flame 35 by the relative movement of said parts whereby the reflected gaseous products of combustion are drawn away from the points of combustion.

In testimony whereof I have hereunto set 40 my hand.

JAMES M. SWEENEY.
